UNITED STATES PATENT OFFICE.

WILLIAM W. HESSON, OF TORONTO, ONTARIO, CANADA.

TOBACCO PIPE.

1,424,408.

Specification of Letters Patent. Patented Aug. 1, 1922.

Application filed July 5, 1919. Serial No. 308,693.

To all whom it may concern:

Be it known that I, WILLIAM WALLACE HESSON, a subject of the King of Great Britain, and resident of the city of Toronto, 5 county of York, Province of Ontario, in the Dominion of Canada, have invented certain new and useful Improvements in Tobacco Pipes, described in the following specification and illustrated in the accompanying 10 drawings, that form part of the same.

The principal objects of this invention are to eliminate the undesirable conditions following the continued use of a pipe and to enable the removal of parts that may be 15 come saturated or burned and to devise a pipe in which the separable parts will be free from leakage and other conditions permitting the accumulation of nicotine.

The principal feature of the invention 20 consists in the novel construction and arrangement of parts whereby a removable bowl lining is securely held in an outer bowl and is directly connected with the mouth piece in a continuous sealed passage.

25 The drawing is a vertical sectional view through the pipe bowl and stem.

In the use of a tobacco pipe, it is extremely desirable that the pipe should not be used when the bowl becomes saturated with nicotine 30 as it results in the noxious fluids being carried to the mouth and it is the purpose of this invention to eliminate this condition by providing a structure of pipe in which the lining may be replaced.

35 It has been previously proposed to provide removable linings but as far as I am aware the structures produced have not been suita-

ble in that there has not been maintained a definite sealed connection between the bowl lining and the mouth piece.

In the construction herein shown, the bowl is open at the bottom and the lining 24 which may be of any suitable material is inserted from the bottom so that the upper edge abuts the shoulder 25 at the top of 45 the bowl and a cap 26 is threaded into the bottom against the lining. The lining is provided with a radial hole 27 which may be tapered or threaded as desired to receive the inner end of a tubular stem 28 50 which is threaded into the removable mouth piece which definitely connects the mouth-piece with the inner bowl or lining in a sealed passage and there will be no recess in which nicotine or undesirable elements 55 may secrete.

When the bowl lining becomes saturated or burned to an undesirable degree, it is merely necessary to remove the mouth piece and inner stem and the cap 26 and the lining 60 may then be withdrawn and replaced with a new one.

What I claim as my invention is:—

A tobacco pipe, comprising, an outer bowl member formed of two separable portions 65 one of which has a shoulder, threaded together, a removable bowl lining of absorbent material adapted to fit snugly within the outer bowl and to be clamped between the shoulder portion and the other portion 70 of the outer bowl, a mouth piece, and a tubular extension from said mouth piece entering the side wall of said lining at the bottom.

W. W. HESSON.
